THUMB-OPERATED TRIGGER SAFETY

Casimer M. Niesp, Buffalo, N. Y.

Application January 23, 1956, Serial No. 560,662

2 Claims. (Cl. 42—70)

This invention relates to guns, under which term I include rifles and other types of firearms provided with automatic locking means to prevent unintentional discharge of the gun.

Safety devices are now provided by manufacturers of guns, rifles and the like, to manually control the firing of a gun or other firearms. Invariably, however, such manually-controlled safety devices or means are subject to the user of the gun applying force to some member of the mechanism of the gun and even though manually-controlled against discharge of the gun, such controls as now provided in a gun fail to function properly should the user, under excitement or otherwise, fail to hold the manually-controlled member of the safety means against actuation.

In most, if not all gun structures, the discharge of the gun occurs upon manipulation of a trigger or triggers included in the gun structure. When accidentally dropping the conventional gun as now manufactured with means to manually control the firing thereof, it might result in a twig from a shrub or other growth entering the trigger guard of the gun and causing movement of the trigger, with the result that through the connection of the trigger with the so-called safety mechanism of the gun, the latter will be unintentionally discharged with the possibility of injuring, and even causing the death of the user of the gun or a person nearby.

It is the purpose of this invention to provide the gun with a projecting element forming part of automatic locking mechanism or a projecting part thereof which I preferably refer to as a safety button and which is movable along the length of the gun stock for convenience in locking the same against actuation and which is connected with the trigger mechanism designed to operate or at least allow operation of the firing mechanism of the gun.

With this in mind and to basically disclose the essential features of this invention in one exemplary form, I have provided the accompanying drawings in which Fig. 1 is a side elevation of a conventional type of gun used for sporting or hunting purposes.

Fig. 2 is an enlarged sectional side elevation of that part of the stock of a gun to which the inner end of the gun barrel is attached, the gun having its locking mechanism shown in locked position.

Fig. 3 is a planar sectional view of the stock portion of a gun, the latter being equipped with my invention.

Fig. 4 is a view similar to Fig. 2, the gun having its locking mechanism in unlocked position; the wooden interior forming the stock being omitted.

Fig. 5 is a transverse section taken through the stock of the gun.

Fig. 6 is a detached perspective view of the lock device whereby the trigger or triggers of the gun are automatically locked and so retained.

Fig. 7 is a perspective view of a portion of the prime actuator automatically maintained in locked position and in operative connection with other parts of the mech-

2

anism designed to place said prime actuator in active position.

Guns of this type are usually provided with one or more barrels which are attached to the stock of the gun, and with a sheet metal housing shaped, stamped or otherwise fashioned to fit over the stock and protect certain parts of the mechanism confined in the gun at this region and to prevent access to parts controlling the firing mechanism of the gun (not shown) but apparent to those skilled in the art to which this invention pertains. The housing is fashioned to conform to or blend into the exterior surface of the gun. In this exemplary form of my invention shown, the trigger guard at least partly surrounds the trigger or triggers of the gun, which invariably project downwardly from the stock and are designed to be tripped or actuated to cause actuation of the firing pin and the firing of the ammunition with which the gun is loaded, as is well known to those skilled in the art.

20 The stock of the gun, which I designate by the numeral 7, is usually constructed of walnut or other hardwood provided with an exterior depression or depressions 7a, best shown in Fig. 2, to receive the metal housing and to provide a smooth continuity for the exposed portions of 25 the gun at this region. In other respects the gun shown in the drawings is of the type mostly used for hunting purposes and is intended to prevent many accidents which inadvertently take place, particularly since in hunting, a carefree attitude is commonly displayed during the excitement occasioned when an animal or bird is shot. In such excitement all necessary precaution that should be taken to prevent firing of the gun is unconsciously disregarded. It is the purpose of this invention that at all 30 times, and especially during periods of excitement, the trigger or triggers of the gun be automatically locked against movement, even though direct pressure were applied to the trigger or triggers of the gun.

Referring to the drawings in detail without any intention to restrict the invention to any type of gun, the gun shown has the stock 7 and may have two barrels 8 projecting forwardly from the stock, one of which only is shown. The reference numeral 9 represents a sheet metal housing in the form of a stamping which joins the barrel or barrels 8 to the stock and is provided with a trigger guard 10 within which the free ends of triggers 11 terminate with sufficient space within the guard to permit the triggers to be actuated when it is desired to fire the gun.

The housing 9 is in the form of a metallic loop which 50 embraces the wooden portion of the stock, as best shown in Fig. 5, and has two side members 12, 13, connected at the top by a bridge member or wall 14 and at the bottom by a transverse member 15 which holds the sides of the housing in a rigid manner and in spaced relation, 55 thus fully enclosing the wooden portion of the stock along this region. The triggers 11 project outwardly from the stock and are partly surrounded by the trigger guard 10 so that the triggers are normally protected against accidental movement and the firing of the gun.

60 Within this loop housing, the wooden stock portion is gouged or hollowed out to provide a chamber 16 receiving movable and immovable parts of my improved safety mechanism. For example,—slidably arranged underneath the bridge member or wall 14 of the loop housing 9 is what I term the prime mover or actuator of my improved safety mechanism. This prime mover consists of a slide piece 17 in which a longitudinal slot 18 (see Fig. 7) is formed. The said slide piece 17 is longitudinally movable in the chamber 16 and is positioned underneath the bridge wall 14. It has extending upwardly therefrom a thumb piece 20. Depending from the thumb piece 20 is an ear 21 which extends through a slot 22 in the

bridge member or wall 14. This thumb piece 20 is adapted to be actuated by a thumb or finger of the user of the gun so as to counteract the force of a spring 23 within the chamber 16 interposed between the prime mover, or more particularly the actuator or slide piece 17 and a fixed point in the stock of the gun, shown at 24. Said spring serves at all times to move the slide piece 17 in the direction opposite that indicated by the arrow 25, shown in Fig. 2, and thus maintain the finger or thumb piece 20 at the inner end of the slot 22 in the bridge member or wall 14 of the housing.

Within the chamber 16 in the stock is a lever-retaining cage or carrier 26. This cage or carrier is fastened immovably within the chamber 16 and is formed of a flat piece of metal bent upon itself to provide two spaced-apart side members 27 between which a lock lever 28 is positioned and pivoted to said side members, as at 29. The lock lever has its upper end 30 projecting above the upper end of the cage or carrier and its lower end provided with a lock lug 31 and projecting beneath the lower end of said cage or carrier. The upper end of this lock lever extends through the opening 18 in the slide piece 17 which it snugly fits so that upon movement of said slide piece longitudinally within the chamber 16 said lock lever is swung on its pivot 29. The said lock lug 31 engages a complementary lock lug 32 formed on each trigger and is at all times locked against movement until it is the intention to fire the gun, at which time the user of the gun must press the finger or thumb piece 20 forwardly, as viewed in Fig. 4 or in the direction of the arrow 25 in Fig. 2, to strain the spring 23 on the slide piece 17, whereupon the latter is moved in a like direction with the result that the lock lever 28 is swung on its pivot from the position shown in Fig. 2 to that shown in Fig. 4, and the lower end thereof disengages itself from the lock lug 32 on the trigger, thus permitting the latter to be moved and the firing or concussion pin (not shown) of the gun actuated in the usual manner to cause the gun to be fired. Immediately upon firing the gun all parts under the action of the spring 23 will return to normal position, which is that in which the lock lever 28 is locked within the cage or carrier 26 so as to lock the trigger against movement.

Where in the claims "triggers" are referred to, it is my intention to embody a single trigger or any number of triggers, depending on the number of barrels included in the gun, and as will be understood by those skilled in the art to which this invention relates, each trigger may have associated therewith complementary firing elements (not shown) but commonly understood as to their construction and functional purpose.

Having thus described my invention, what I claim is:

1. In a mechanism to prevent firing a weapon until a thumb-piece is moved after the firing hand of the user is in final position to pull the trigger, a safety mechanism for insertion into the chamber of a gunstock and comprising a trigger pivotally mounted in the lower portion of

said chamber and having a lock lug extending into said chamber, a lock lever pivotally mounted at its central portion within said chamber and having a locking lug portion on the lower end thereof, a slide piece slidably mounted in the upper portion of said chamber, said slide piece having a slot adjacent each end thereof, the slot in the forward portion of said slide piece receiving the upper end of said pivotally mounted lock lever, a spring continuously urging said slide piece rearwardly to maintain the locking lug portion on said locking lever in engagement with said trigger locking lug, a thumb piece actuator slidably mounted on the upper surface of said gunstock above said chamber, an ear depending from said thumb-piece and extending into the rear slot of said slide piece, said thumb-piece being actuated by a thumb or finger of the user of the gun so as to contract the force of said spring to pivot said lock lever and to disengage said lock lever locking lug portion from said trigger locking lug to permit the manual manipulation of the trigger by the user of the gun.

2. In a mechanism to prevent firing a weapon until a thumb-piece is moved after the firing hand of the user is in final position to pull the trigger, a safety mechanism for insertion into the chamber of a gun stock and comprising a trigger having a locking lug extending into said chamber, a lock lever pivotally mounted intermediate its ends and having a locking lug portion on the lower end thereof engageable with the locking lug on said trigger, a slide piece longitudinally movable in the upper portion of said chamber and positioned underneath the upper wall of said chamber, said slide piece having an elongated slot for receiving the upper end of said pivotally mounted lock lever, a thumb-piece actuator slidably mounted on the upper surface of said gun stock chamber and having a portion thereof slidably connected with said slide piece to form a driving connection therewith to enable said slide piece to be moved in a reverse direction to disengage said lock lever from said trigger locking lug to unlock the trigger to permit manual actuation of the trigger, and a spring continuously urging said slide piece in a direction to pivot said lock lever into engagement with said trigger locking lug, said spring being attached to said thumb-piece actuator portion below said slide piece to prevent downward disconnection of the slide piece from said portion.
